STAND TO SUPPORT COLLECTING COVERS
OR THE LIKEAnders Erik Gustaf Hedenström
Stockholm, SwedenApplication September 29, 1941, Serial No. 412,963
In Sweden August 27, 1940

4 Claims.

(Cl. 45—60)

This invention relates to a stand adapted to support collecting covers or the like, said stand being provided with supporting members for the covers, which members are swingable in a vertical plane at least 180°, each supporting member being provided with a device for detachably holding a cover.

According to one feature of the invention the holding device for each cover is constructed and connected with the supporting member in such manner that the cover is slidable in a plane parallel to the swing axis of the supporting member.

According to another feature the holding device for each cover is constructed and connected with the supporting member in such manner, that the cover is also turnable in a plane parallel to the swing axis of the supporting member.

Other features of the invention will appear from the following description and the claims.

In the accompanying drawings:

Fig. 1 is a top view of a stand in the form of a table.

Fig. 2 shows a vertical section of the same on the line II—II in Fig. 1.

Fig. 3 is a top view of the table supporting a collecting cover in open position.

The stand is provided with four legs 1 (the lower part of the legs being omitted in Figure 2), which are connected with each other by four bolts 2. Two of these bolts are connected with a number of vertical plates 3 at equal distances from each other and between which a number of arms 4 are swingably mounted on a bar 5 extending through all of the plates 3 and positioned a little on the side of the middle between the ends of each arm 4. On the outside of the outermost plates 3, side detachable supports 6 are provided having their upper sides on the same level with the upper sides of the arms 4 when these take the horizontal position shown with dotted lines in Fig. 2 in which position all of the arms are positioned in the same horizontal plane and together with the side supports form a table. Three of the bolts 2 support rollers 7 of rubber or the like which serve as stop members for the covers 8, as will appear from the following. Each arm 4 is provided on one side with a button 9 having an elongated head which is adapted to pass through an elongated aperture 10 in the back of the cover 8, when this is positioned so that the longitudinal direction of the aperture 10 is parallel to the swing axis of the arms 4. When the cover is turned from the said position, the longer axis of the head of the button 9 makes an angle with the longitudinal direction of the aperture 10.

Further, each arm 4 is provided on the same side and at one of its ends with a bent tongue 11 which is adapted to catch the end of the cover back, when the cover 8 has been put into the position shown in Fig. 2.

In order to attach a cover 8 to an arm 4 this is swung to the position shown in full lines in Fig. 2, and the cover is placed in such position that the aperture 10 is right above the button 9 and parallel to the pivotal axis of the arms 4, so that the head of the button 9 may pass through the aperture 10. Thereupon the cover is turned 90°, so that the cover back will be parallel to the arm 4, and is thereafter slid so that the end of the cover back engages under the tongue 11. The cover is now attached to the arm 4. When the cover 8 is to be without use it is closed so that the side covers take a vertical position as shown in the upper part of Fig. 2. On account of the eccentric position of the swing axis 5 the cover 8 rests by its own weight (and the weight of any papers contained in the same) on the upper roller 7 to the left in Fig. 2. By swinging the arm 4 clockwise (according to Fig. 2) the cover may now be turned to its lower position, in which the cover rests on the lower roller 7 to the right, and also in this case on account of the eccentric position of the swing axis.

When a leaf or a card is to be inserted in or withdrawn from the cover or an annotation is to be made on the leaf or card the arm 4 is swung counterclockwise (according to Fig. 2) to its upper position, whereupon the cover is opened, the other arms 4 which hold the downwards positioned covers serving together with the side supports 6 as a supporting table for the opened cover (Fig. 3). By the fact that the cover is slidable on its supporting arm the cover may be moved relative to the writer to a suitable position for handy writing. By the fact that the cover also is turnable on its supporting arm it is possible for the writer to work at several adjacent stands and to bring any cover to a suitable position for the writer.

One end of each arm 4 has an inclined end surface which in the position of the arm 4, in which the cover hangs downwards, is directed upwards, and on which a label may be applied which shows the number, contents or the like of the cover.

What I claim is:

1. A stand adapted to support collecting covers or the like, a plurality of collecting covers, supporting members for said covers, said members being swingably mounted on the stand to swing in a vertical plane through a range of at least

180°, each supporting member being provided with a device for detachably holding a cover, said holding device comprising a stud or the like fixed on one of the parts connected and engaging in an elongated aperture formed in the other part, said stud being slidable in the longitudinal direction of said aperture through a substantial portion of the length of the cover and having a head which is laterally elongated and narrower than the aperture in its longitudinal dimension so that it is able to pass through the aperture only in a turned position of the cover which forms a right angle to the normal position of the cover.

2. In a stand for supporting collecting covers or the like, and provided with supporting members for the covers, which members are swingable in a vertical plane through at least 180°, collecting covers held by said supporting members, each supporting member being provided with a device for detachably holding a cover, said holding devices comprising a stud, fixed on one of the parts to be connected and having a laterally enlarged head, engaging in an elongated aperture formed in the other part, the lateral extent of the head of the stud being greater than the width of the aperture and the longitudinal extent thereof being no greater than the width of the aperture, said stud being slidable in the longitudinal direction of said

aperture through a substantial portion of the length of the cover.

3. A stand for supporting collecting covers or the like comprising, a plurality of collecting covers, supporting members for the covers, means for pivotally holding said supporting members so as to swing in a vertical plane through at least 180°, and an elongated slot-and-headed-stud connection for detachably and slidably connecting each cover with its supporting member to enable the cover to slide in a direction transverse to the pivotal axis of the supporting member through a substantial portion of the length of the cover.

4. A stand for supporting collecting covers or the like comprising, a plurality of collecting covers, supporting members for the covers, and means for pivotally mounting said supporting members to swing in a vertical plane through at least 180°, each supporting member and its supported cover being provided with an elongated slot-and-headed-stud connection for detachably and slidably holding the cover on its supporting member to enable the cover to slide in a direction transverse to the pivotal axis of the supporting member through a substantial portion of the length of the cover and also to turn in said plane.

ANDERS ERIK GUSTAF HEDENSTRÖM.
